UNITED STATES PATENT OFFICE.

ERIC HARTWIG WHYTEHEAD, OF LEEDS, ENGLAND.

SIGNALING AND TRAIN-STOPPING APPARATUS.

1,363,070.

Specification of Letters Patent. Patented Dec. 21, 1920.

Application filed January 23, 1918. Serial No. 213,938.

To all whom it may concern:

Be it known that I, ERIC HARTWIG WHYTEHEAD, a subject of the King of Great Britain, residing in Leeds, England, have invented certain new and useful Improvements in Signaling and Train-Stopping Apparatus, of which the following is a specification.

This invention relates to train-carried apparatus of the kind wherein mechanical inter-action between stationary track obstacles and a train-carried contact ramp device causes the automatic actuation of mechanism for indicating within the engine cab of a train the state of track signals. It consists in improved construction and arrangement of parts as hereinafter described, the object being to produce apparatus of the above kind which is simple and reliable in action, is cheaply installed and economical in regard to running costs, and which may alternatively or additionally be adapted to control in any known manner the supply of motive power to the engine or the brake mechanism of the train.

In the improved apparatus mechanical interaction with a track obstacle or accidental breakage and interference with the normal position of the contact-ramp device results in the manipulation of a piston-valve or rotary valve (hereinafter referred to as the "initiator") in a manner to reverse concurrently in a pair of double-acting cylinders, the direction of fluid pressure (which may be above or below atmospheric pressure and is hereinafter referred to as "operating medium") whose motive-power acts on a piston in each of the aforesaid cylinders, holding them normally in a non-operating position and wherein the conjoint movement into the operating position of the two individual pistons when initiated by the operation of the initiator is prevented by a movable catch or detent (hereinafter referred to as the "selector") in such a manner, that when one cylinder piston is free to move, the other cylinder piston is locked and vice-versa.

The relative position of the "selector" and the consequent selection for operation of one of the pistons is determined by the state of track-signals acting on the selector in any known manner through the medium of mechanical or electrical means and in such a way that a danger-signal will be given unless an auxiliary action, taking place concurrently, causes the selector to

change its position, thus permitting the actuation of the "line clear" signal and at the same time preventing the operation of the danger signal.

Each of the aforesaid pistons has a separate function, one piston (hereinafter referred to as "line-clear indicating device") being adapted to serve to actuate visible or audible train-signals indicating "line-clear," the other piston (hereinafter referred to as "danger-device actuator") being arranged to actuate similar signals serving as danger indications. The latter piston may additionally or alternatively be adapted to actuate devices controlling the supply of motive power to the engine or actuate devices controlling the brake mechanism of the train.

The arrangement of the whole apparatus is preferably such, that the "selector" normally permits the unrestrained operation of the "danger-device actuator," that is to say, the actuation of the "initiator" will only result in the operation of the "line-clear indicating device," if the selector is being conjointly constrained to unlock it, the action of the "danger-device actuator" being then simultaneously prevented.

A further feature of the apparatus is the automatic locking in its operated position of the "initiator" until manually released and the separate locking in its operated position of the "danger-device actuator," which latter can only be conditionally released. While thus, after completion of its performance, the automatic return to "normal" of the "line-clear indicating device" and of the signals actuated thereby is rendered possible by the release of the "initiator" from its operated position, a similar return to "normal" of the "danger-device actuator" and corresponding cessation of the action of devices operated by the latter may be made dependent on the separate and prior actuation of known devices (hereinafter more fully referred to) serving to control the speed of the train. The advantages claimed from such arrangements are that while the actual control of the train is not being taken out of the hands of the train personnel, they are virtually compelled, in the case of a danger signal being received, to take such action as will reduce the speed of the train or stop the train, according to requirements, or according to whether a distant signal or a home signal is being passed at danger.

If it be desired to leave control in the

- driver's hands when passing warning track-signals at danger, such as distant signals, and to automatically stop the train (beyond the control of the driver) when passing stop 5 track signals, such as home or station signals, two sets of the improved apparatus may be fitted to each train, one for coöperation with track obstacles associated with warning signals and adapted to reproduce 10 on the train the state of such track signals as hereafter described, and the other in conjunction with track obstacles associated with stop signals and adapted to directly operate upon the steam-regulator and the brake 15 mechanism of the train, or, alternatively, upon the steam-regulator only or the brake mechanism only.

In the arrangement described above each 20 of the cylinders constituting the pair of double-acting cylinders and pistons may be replaced by a set of cylinders with pistons, but it is not considered necessary to illustrate such arrangement.

The invention will be described with reference 25 to the accompanying diagrammatic drawings in which Figure 1 is an elevation, partly in section, showing the general arrangement of a complete apparatus constructed according to the invention, and also 30 a portion of a rail track, a part of a track obstacle, and some electrical circuits.

Fig. 2 is a sectional elevation, to enlarged scale, of parts of the apparatus depicted in Fig. 1 and represents a convenient form of 35 train equipment arranged in accordance with the invention and in which the operating medium may be steam, compressed air or liquid at a pressure above atmospheric pressure.

40 Fig. 3 is a sectional elevation of the initiator portion of the train equipment in Fig. 2, modified to allow of a reduced fluid pressure or a fluid pressure below that of the atmosphere being adopted as the operating 45 medium of the whole apparatus.

Figs. 4 and 5 are details of a further modification in the initiator portion of the train equipment and represent each a rotary valve device, respectively adapted for use in cases 50 where the operating medium is a fluid pressure above or below atmospheric pressure.

Fig. 6 is a detail showing a modified arrangement of the selector device included in the apparatus illustrated in Fig. 1.

55 In the various figures the same parts are denoted by the same reference characters.

The apparatus, hereinafter described, lends itself particularly to variations and modifications in construction and design, 60 obvious to those versed in the art, which while modifying or varying the form or *modus operandi* of individual components, do not constitute a departure from the spirit and nature of the invention as a whole.

65 The engine carried contact ramp device

may be of a compound character and may, as shown in the drawings, include a ramp member T for coöperation with the initiator, the said member being mounted on a vertically sliding rod 13' which slides in 70 guides 117, 117^a, carried by a known track obstacle contact-device of the vertically sliding type and comprising a depending contact-ramp 118, Fig. 1, moving against the action of a spring 204 in a casing 205 carried by the longitudinal frame member 119 and fitted on its lower extremity with a contact roller 200, which on encountering a stationary track-obstacle, preferably of the double-inclined-plane type, such as the rail 80 D, ascends vertically against the action of the spring 204. The rod 13' is, according to this invention, supported on the axle 203 of the contact roller by means of the fork 132 formed on its lower end, the fork being in 85 no way secured to the roller. A track obstacle, a portion of which is shown at D, is fixed in any desired position between the rails R of the permanent way at all places where it is desired to convey signals to the 90 train. The ramp T is electrically insulated from the rod 13' by insulating material 12. The rod 13' being separately supported on the axle of the contact-roller, insures that an accidental detachment of the latter, or 95 breakage of any part of the contact ramp T, will cause the removal of the ramp from the normally held position shown in Figs. 1 and 2. Variations in the height of the vehicle under different loads do not interfere 100 with the working of the apparatus, as the inclined plane and the vertical contacting plane of the ramp T may be so proportioned that the vertical height of the inclined plane of the ramp T is the same as the minimum 105 lift possible under the most adverse conditions of load.

The "initiator" A, as shown to an enlarged scale in Fig. 2, is of the slide-valve or piston-valve type and consists of a cylindrical casing 60, containing two valve pistons 16, 17 and a special piston head 18, all carried by the laterally movable piston rod 15. The piston rod is provided with a collar 16^a for limiting the length of its 115 stroke and with a tooth 46 (shown also in dotted lines in its operated position) which serves to lock the piston in that position by interaction with the spring-held catch 44 movable on a fixed pivot 45. This catch 120 can be moved to its releasing position by manual depression of the knob 56 forming part of the spring-supported rod 37 moving vertically in guides 50, 52 and acting on the lever 42 which moves on the fixed pivot 125 43. This lever may be counterweighted, so as to wholly or partly replace the action of a spring (not shown) which supports rod 37.

The operating medium is admitted to the 130

initiator A by way of conduct-pipe F (partly shown) through port 2. The pipe F has a branch 13 admitting pressure at the same time through port 14 on to the 5 cup-shaped end of the piston head 18, thus tending to press back piston rod 15 to the extreme right.

47, 48, 49 are exhaust ports in the initiator casing. In the shown "normal" position of the initiator valve-pistons the fluid pressure is acting through port 3 by way of connecting-pipe 4 and port 5 on the twin-piston P^1, P^2 of the line-clear indicating device C^1 and concurrently through port 6 10 in the cylinder wall 61 on the piston P of the "danger-device actuator" C. The other end of the two cylinders communicates through ports 10 and 9 by way of connecting-pipe 8 through port 7 in the initiator 15 casing and exhaust port 47 with the atmosphere. A reversal of this non-operative condition takes place when the initiator piston rod is moved to the left by the lifting to its full extent of the ramp T and similarly, when the piston rod under the action 20 of the fluid pressure on piston-head 18 is moved to the right to the full extent possible when in consequence of accidental breaking the ramp T is withdrawn.

25 The necessary modification in the design of the initiator, when it is desired to substitute the action of a fluid pressure below atmospheric pressure as operating medium of the whole apparatus, is shown diagrammatically in Fig. 3.

The cylindrical casing of this modified initiator A^1 , Fig. 3, contains the four valve pistons 83, 84, 85 and 86 carried by the piston rod 81 which is furnished with a collar 82 for limiting its outward travel and passes through the gland 94 and is provided with a tooth 97 (shown in dotted lines also in its operated position) serving to lock the piston in its operated position 40 by inter-action with the spring held catch 95 movable on a fixed pivot 96 and capable of being operated in the manner above described with reference to catch 44. The operating medium or vacuum acts through 45 conduct-pipe F^1 by way of the branches 89, 98 communicating respectively with ports 90 and 91. The exhaust ports are denoted by 92 and 93. The modified initiator A^1 is in action identical with that shown in Fig. 2, the fluid pressure acting in its normal 50 position through port 88 by way of communicating-pipe 8 on to pistons P, P^1, P^2 respectively, while the other end of the cylinders now communicates through ports 6 and 5 by way of connecting-pipe 4 and exhaust-port 92 with the atmosphere. In its 55 operative position or when the ramp T is entirely removed through accidental breaking of the train-carried contact-device, the 60 position of the valve-pistons is changed in

such a manner as to reverse the non-operative conditions just described.

A further modification of the initiator, showing, diagrammatically, construction of the rotary-valve-type, is represented in Figs. 4 and 5.

Fig. 4 represents the rotary valve in the operated position, the key-arm 110, carrying the weight 111, having been raised through an angle of about 45 degrees, thereby correspondingly rotating the valve-key 105 in the valve casing 100 and thus connecting the fluid pressure inlet port 103 through key-channel 115 with exit-port 102, thereby admitting the operating medium 75 (steam, compressed air or liquid under pressure) from conduct-pipe F^2 through connecting pipe 8 to left hand side of the pistons P, P^1, P^2 .

The engine-carried contact-lever suitable 80 for use with this modification as shown in Fig. 4, is represented by a rod 112 mounted with interposed insulating material 113 on the sliding rod 114 (partly shown) of the engine contact-device 118 carried by frame 90 member 119. Rod 114 would be supported, similarly to rod 13', on the axle of the contact-roller 200, and is thus lifted vertically when the former rides up a track-obstacle. Accidental breakage of the roller will thus 85 also cause the rod 112 to drop, removing its support from the weighted valve-key arm 110 thus causing the latter to assume a vertically depending position, when the valve-channels 115, 116 will be in a position 90 incidentally coinciding with that shown in Fig. 5.

Fig. 5 represents the normal position of the valve-key of the same rotary valve when 95 vacuum is the operating medium of the whole apparatus. In this modification of the design port F^3 is connected to the fluid pressure conduit-pipe (not shown).

Variations in the height of the contact-lever carrying vehicle due to different loads 100 will not affect the working of the rotary-valve type initiator by reason of the particular elongated form of the ports 101, 102, 103, 104 in the valve casing, if the variations are within the limits of a vertical lift 115 representing a rotation of the valve-key of between 45 and 90 degrees.

This type of initiator may be conveniently locked in its operated position by engagement of the spring-held catch 108, pivoted 120 at 109, with nose 107 of the valve-key-carried quadrant 106 (Fig. 4).

The "line-clear indicating device" C^1 and the "danger-device actuator" C (referred to collectively as "actuating devices") as 125 shown in Fig. 2 consist of a twin cylinder 62 having common cylinder heads 62^a and 62^b and being separated by the common cylinder wall 61 and intercommunicating through ports 6 and 10. This particular ar- 130

arrangement of the cylinders is, however, optional and immaterial to the working of the apparatus; they may be separated from one another and occupy any position suitable to 5 meet particular requirements.

The piston P and twin pistons P¹, P² are fixed on piston rods 19 and 19^a respectively which latter are carried through the stuffing boxes 58 and 59 of the common cylinder-10 head 62^b and are further positioned by the guide plate 22, which latter also carries the pivot 23 on which a counter-weighted selector S is movable. The counter-weight 28 of the selector S is so adjusted, that while 15 reducing the energy necessary to move the selector on its pivot to a minimum, it will allow of it occupying normally the position shown in the drawing in full lines. The particular way of mounting the selector or 20 its particular form or the manner in which it locks the actuating devices may be greatly varied to suit individual requirements, one of the possible modifications being represented in Fig. 6 and hereinafter described.

25 The piston rods 19 and 19^a are provided with teeth 24 and 25 respectively which, when inter-acting with the claws of the V-shaped selector head 26 and, depending on the position which the latter occupies at 30 the time of the conjoined initiation of the movements of the pistons, will lock the one or the other of the actuating devices. Piston rod 19^a is further provided with stops 20, 21 which serve to suitably limit its 35 stroke.

The selector may be connected with or 40 carry directly tell-tale indicators showing in a forcible manner its relative position occupied for the time being. One such device is represented in Fig. 2 by a two-colored plate 33 carried by the solenoid-core 57 and showing alternately one of its colors through window 34 in a stationary screen (not shown). The relative position of the 45 selector S in the arrangement of apparatus shown, is controlled by its being mechanically connected with the solenoid-core 57 of the solenoid M. This latter may be substituted by an electro-magnet of whose 50 armature the selector forms part or to which it is mechanically connected.

The solenoid or the electro-magnet may be energized when an exteriorly situated 55 switch or circuit breaker operated by direct mechanical connection to the track signals or special signals or from signal cabins, permits of the completing of an electric circuit in the known manner at the time of the inter-action of the train-carried contact lever 60 with the track obstacle.

The source of electric energy may be 65 train-carried generators, the electric current passing by way of the electrically insulated train-carried contact lever from a collecting

shoe or roller fitted to its lower extremity, to the insulated stationary track obstacle, through suitable insulated wires to the circuit breaker, returning from there through the rails and the wheels and the frame of the vehicle. In that adaptation the electromagnet or the solenoid is preferably actuated by 70 a separate electric circuit deriving its energy from a common or a special source and closed by a weak-current relay which latter is protected by a fusible conductor, or safety 75 fuse, of such dimensioning that any strong electric current passing through it as a consequence of accidental short circuiting, will "blow" the fuse while not preventing the 80 passage of the normal operating current, which is of suitably low amperage by reason of the comparatively high resistance of the conduits leading to the circuit breaker (assured if necessary by the provision of separate resistance coils or the like, situated 85 close to the circuit breaker).

The electric energy may alternatively be supplied by exteriorly situated generators or existing track-circuits, being conveyed to the vehicle and apparatus thereon in any 90 known manner by special collecting shoes or the like fitted on the vehicle.

Suitable electrical installations are indicated in Fig. 1 and comprise (1) an electric switch or circuit breaker 208, 209, attached 95 to and directly operated by the semaphore or other track signal whose indications are to be reproduced on the engine, (2) an electrically insulated conductor (telegraph wire for instance) 206, 214 (with or without a resistance 207) connecting the track obstacle D through the circuit breaker to the rails of the permanent way or to earth, and (3) train carried sources of electric energy, including for instance storage cells or batteries, B, B¹, a weak current-relay W-R with its armature 190 pivoted at 175 and protected by a low-tension fuse E, the circuit wires 178, 179, 180 and contacts 176 and 177, and the circuit wires 171, 172 and 173 100 to earth 174.

A change of position of the selector in conjunction with a change of state of the ordinary or special track signals, may alternatively be effected by direct mechanical 105 connection of the selector to specially provided engine-carried contact levers which interact with movable track ramps, the position of the latter being determined by the state, for the time being, of the ordinary or 110 special track signals.

Alternatively, the engine-carried contact device, which on inter-action with the stationary track-contact operates the initiator 115 of the apparatus, may carry an additional 120 sliding rod which, on a conjoined inter-action with a movable signal-controlled track-ramp taking place, will change the position 125 of the selector.

The line-clear indicating device C¹ in Fig. 130

2 of the drawings as shown is actuating, when in its operated position, a small whistle W through the agency of the operating medium itself, port 11 of the lower cylinder being then uncovered.

When a liquid under pressure is the operating medium of the whole apparatus, a similar whistle, having an independent operating medium, may be actuated by the 10 movement of piston rod 19^a by direct mechanical connection thereto in the manner similar to that indicated in Fig. 6 or any known manner.

Visible signals such as miniature semaphores, colored disks or the like may additionally or alternatively be actuated by the 15 same line-clear indicating device.

The "danger-device actuator" C in Fig. 2 is shown as operating a valve V by direct 20 mechanical connection to the piston rod 19 through bell crank lever link 30 mounted on the fixed pivot 31. The piston P, part of piston rod 19 and parts of the lever link 30 are shown in their operated position in dotted lines. The operation of valve V admits steam to the engine whistle, its automatic sounding being the danger indication, but the whistle may alternatively be actuated by direct mechanical connection to its customary lever or in any known manner and further the device may additionally or alternatively actuate contrivances controlling the supply of motive force to the engine or devices operating the brake mechanism of the train.

For purposes of more convenient attachment of such additional devices to the actuating piston rod, the latter may be carried through both ends of the cylinder.

40 In the modified actuating devices partly shown in Fig. 6, the piston rod 150 passing through guide 152 and piston rod 151 passing through guide 153, respectively act through crank-connecting rods 157 and 158 on pivoted disks 159, 163. In the case of the line-clear indicating device the pivoted disk 159, connected at 161 to connecting rod 157, is by the action of piston rod 150 rotated through an angle corresponding to the 45 movement of the rod and is thus able, by means of the pin 170, the lever 165 on fixed pivot 166, and linkage 167, to actuate a valve 168 of a whistle W¹ associated with the line-clear indicating signals. In the case of the 50 danger-device actuator the crank-connecting-rod 158, pivotally connected at 162 to the disk 163, rotates directly the key of cock V¹, thus permitting fluid pressure above or below atmospheric to operate danger signals or other devices in any known manner.

60 The selector S¹ in that arrangement of apparatus instead of locking the piston rods in the manner heretofore described, performs its duty by locking or liberating the 65 movable disks 159, 163 respectively.

The arrangement shown in Fig. 2 for separately locking the danger-device actuator in its operated position consists of a piston-rod-carried tooth 29 (shown in its operated position by dotted lines) which engages in 70 that position with the spring-held catch 35 mounted on the fixed pivot 36, thus preventing the piston rod from returning to normal. The catch 35 cannot be released by the manual depression of knob 56 unless the 75 horizontal lever-rod 55, sliding in guides 53, 54 constrains the tongue 47 carried by and pivoted on rod 37 to engage the lever-end of the catch 35. Rod 55 is shown as being mechanically connected to the lever L pivoted at 58 and correlated with the engineer's valve or steam regulator (not shown) in such a manner, that the tongue 47 is only held in the operative position (that shown in full lines) when the lever of the engineer's valve has previously been moved to the "shut" position which is that indicated in Fig. 1 and Fig. 2. The whistle actuated in the arrangement of apparatus shown cannot consequently be stopped from sounding 90 until the steam supply to the engine has been manually shut off.

The lever L pivoted at 58 may additionally or alternatively be correlated with a valve or device admitting air to the train-pipe or with other known means of actuating the brake mechanism of the train. Thus the whistle cannot be stopped from sounding until the brakes have been manually applied.

In the case where the danger device actuator itself operates upon the brake controlling devices of the train, the liberation of these devices and consequent cessation of their action may be made conditional upon the attainment of a predetermined reduction of speed of the train, by connecting lever rod 55 to a train-carried speed controlled device of known construction in such a manner that tongue 41 is constrained to occupy its operative position only when the speed of the train has been reduced to the predetermined maximum.

Having thus fully described the nature of the said invention and the best means I know of carrying the same into practical effect, I 115 claim:

1. In train carried apparatus of the kind herein referred to, a control device normally energized to assume an inoperative position, signal mechanism for indicating a clear track and a train controlling valve carried by the train for indicating danger and retarding the speed of the train, a track ramp, a track signal, means operated by said ramp to shift the control device to an operative 120 position, a plurality of actuating devices adapted to be operated in consequence of the movement of the control device to operative position and selector mechanism controlled by the track signal for permitting one of 130

said actuating devices to operate the signal mechanism for indicating a clear track and locking the other actuating device in inoperative position, or for permitting said other 5 actuating device to operate said train controlling valve and locking said first named actuating device in inoperative position.

2. In train carried apparatus of the kind herein referred to, a control device normally 10 energized to assume an inoperative position, signal indicating mechanism and a train controlling valve carried by the train, a track ramp, a track signal, means operated by the track ramp to shift the control device 15 to an operative position, a plurality of actuating devices adapted to be set in motion consequent on the movement of the control device to operative position, selector mechanism controlled by the track signal for permitting 20 either of said actuating devices to operate said signal indicating mechanism or said train controlling valve, respectively, and means whereby the control device is caused to move to a second operative position 25 on removal of said ramp operated means from operative relation with said control device.

3. In train carried apparatus of the kind herein referred to, a control device energized 30 to assume an inoperative position, a track ramp, a track signal, signal indicating mechanism and a train controlling valve carried by the train, means operated by the track ramp to shift the control device to an 35 operative position, a plurality of actuating devices adapted to be set in motion consequent on the movement of the control device to the operative position, selector mechanism controlled by the track signal for permitting 40 either of said actuating devices to operate said signal indicating mechanism or train controlling valve, respectively, automatically operating means for locking the control device in said operative position, and a 45 manually operating device for releasing said locking means.

4. In train carried apparatus of the kind herein referred to, a control device normally energized to assume an inoperative position, 50 signal indicating mechanism and a train controlling valve carried by the train, a track ramp, means operated by said ramp to shift the control device to an operative position, a plurality of actuating devices 55 adapted to be set in motion consequent on the movement of the control device to the operative position, and selector mechanism for determining which of said actuating devices will impart movement to said signal 60 mechanism or train controlling valve for displaying signals or controlling the supply of motive fluid to the locomotive through said train controlling valve, respectively.

5. In train carried apparatus of the kind 65 herein referred to, the combination with

mechanisms on the train for indicating the state of the track signals, of a pair of inter-connected double acting cylinders with pistons therein, the pistons being operatively connected with said mechanisms and 70 normally retained in inoperative positions, a device communicating with a motive fluid supply source and with the interior of one of the cylinders, said device adapted to conduct motive fluid continuously to one of the cylinders and including a valve casing 75 and a valve constrained by the action of the fluid to assume normally an inoperative position within the casing, a track ramp, means operable by the track ramp for shifting the valve to an operative position thereby causing the direction of flow of the motive fluid within the cylinders to be reversed concurrently, and selector mechanism 80 dependent for automatic operation on the state of the track signals, said selector mechanism in normal position being adapted to permit the unrestrained operative movement of one of the pistons under the action of the motive fluid and to lock the 85 other piston against such movement and vice versa, whereby one of the signal indicating mechanisms is operated and the other remains locked in inoperative position. 95

6. In a train carried apparatus of the kind herein referred to, the combination with mechanism on the train for indicating the state of the track signals, of a pair of inter-connected double acting cylinders 100 with pistons, the piston being operatively connected with the said mechanism and normally retained in inoperative positions, a pressure operating device communicating with the interior of one of the cylinders, 105 said device adapted to conduct motive fluid continuously to one of the cylinders and including a valve casing and a valve and valve rod constrained by the action of the fluid to assume normally an inoperative position, a track ramp, means operable by the track ramp for shifting the valve to an operative position thereby causing the direction of flow of the motive fluid within the cylinders to be reversed concurrently, said 110 means comprising a bracket depending from the train, a vertically sliding spring pressed ramp contact member, a contact roller and axle fitted to the extremity of the contact member, a vertically disposed 115 spindle having at one end a fork supported on the roller axle, and a cam part carried by the other end of the spindle and adapted to bear operatively against said valve rod, and an automatically operated selector 120 mechanism adapted in normal position to permit the unrestrained operative movement of one of the pistons under the action of the motive fluid and to lock the other piston against such movement and vice 125 130

versa, whereby one of the signal indicating mechanisms is operated and another remains inoperative.

7. In train carried apparatus of the kind herein referred to, the combination with mechanisms on the train for indicating the state of the track signals, of a pair of interconnected double acting cylinders with pistons therein, the pistons being operatively connected with said mechanisms and normally retained in inoperative positions, a fluid pressure operated device communicating with the interior of one of the cylinders, said device adapted to conduct motive fluid continuously to one of the cylinders and including a valve casing and a valve constrained by the action of the fluid to assume normally an inoperative position, a track ramp, means operable by the track ramp for shifting the valve to an operative position thereby causing the direction of the flow of the motive fluid within the cylinders to be reversed concurrently, selector mechanism dependent for automatic operation on the state of the track signals, said selector mechanism being in normal position adapted to permit the unrestrained operative movement of one of the pistons under the action of the motive fluid, and to lock the other piston against such movement and vice versa, whereby one of the signal indicating mechanisms is operated and another remains inoperative, means for automatically locking one of the pistons in the operated position, and a device for releasing said locking means.
8. In train carried apparatus of the kind herein referred to, the combination with mechanisms on the train for indicating the state of the track signals, of a pair of interconnected double acting cylinders with pistons therein, the pistons being operatively connected with the said mechanisms and normally restrained in inoperative position, a fluid pressure operated device communicating with the interior of one of the cylinders, said device adapted to conduct motive fluid continuously to one of the cylinders and including a valve casing and a valve constrained by the action of the fluid to assume normally an inoperative position within the casing, a track ramp, means operable by the ramp for shifting the valve to an operative position, thereby causing the direction of flow of the motive fluid within the cylinders to be reversed concurrently, selector mechanism automatically operated and dependent for operation on the state of the track signals, said selector mechanism being in normal position adapted to permit the unrestrained operative movement of one of the pistons under the action of the motive fluid, and to lock the other piston against such movement and vice versa, whereby one of the signal indicating mechanisms is operated and another remains inoperative, means for automatically locking one of the pistons in the operated position and a device for releasing said locking means.
9. In train carried apparatus of the kind herein referred to, a control device operated by fluid pressure to normally assume an inoperative position, a track ramp, signal operating mechanism connected to said controlling device, means operated by said ramp to shift the control device to an operative position for actuating said signal operating mechanism to display a signal on the train, said means being normally disposed adjacent to said control device to limit the movement thereof in response to said fluid pressure whereby the removal of said means permits said control device to assume a second operative position for actuating the signal operating mechanism in like manner.
10. In train carried apparatus of the kind herein referred to, signal operating mechanism carried by the train, a control device for said mechanism normally in inoperative position, a selector device normally preventing the actuation of said mechanism to danger position, a track signal, electromagnetic means for operating said selector device, a switch adapted to be operated by said track signal, a circuit including said switch and a relay, a second circuit including said electro-magnetic means controlled by said relay, whereby said electro-magnetic means is energized according to the position of said track signal to operate the selector device and permit the actuation of said signal operating mechanism and a track ramp for moving the control device to operative position.
11. In train carried apparatus of the kind herein referred to, a control device normally energized to assume an inoperative position, signal indicating mechanism and a train controlling valve carried by the train, a track ramp, a track signal, means operated by said ramp to shift the control device to an operative position, an actuating device for operating said signal indicating mechanism, an actuating device adapted to operate said train controlling valve, both of said actuating devices being energized simultaneously from said control device and selector mechanism controlled by the track signal for permitting one of said actuating devices to operate while the other is locked in inoperative position.
12. In train carried apparatus of the kind herein referred to, a control device normally energized to assume an inoperative position, signal indicating mechanism and a train controlling valve carried by the train, a track ramp, a track signal, means operated by said ramp to shift the control device to an operative position, an actuating device for operating said signal indicating mechanism, an actuating device adapted to operate said train controlling valve, both of said actuating devices being energized simultaneously from said control device and selector mechanism controlled by the track signal for permitting one of said actuating devices to operate while the other is locked in inoperative position.

130

tive position, signal indicating mechanism and a train controlling valve carried by the train, means for operating said control device to move the same to operative position, 5 an actuating device for said signal indicating mechanism, an actuating device for the train controlling valve, both of said actuating devices being rendered operative by the shifting of said control device to operative 10 position and selector mechanism for permit-

ting the functioning of one of the actuating devices and locking the other in inoperative position.

In testimony whereof I have signed my name to this specification in the presence of 15 two subscribing witnesses.

ERIC HARTWIG WHYTEHEAD.
